United States Patent Office

Des. 228,276
Patented Sept. 4, 1973

228,276

TAPE CUTTING DEVICE

Charles A. Bolton, 440 Westridge Road,
Crete, Nebr. 68333

Filed Nov. 22, 1971, Ser. No. 201,253

Term of patent 14 years

Int. Cl. D8—03

U.S. Cl. D8—98

FIG. 1.

FIG. 2.

FIG. 3.

FIG. 4.

FIG. 5.

FIG. 6.

FIG. 1 is a right hand side elevational view of a tape cutting device showing my new design;

FIG. 2 is a front elevational view of the device;

FIG. 3 is a left hand side elevational view of the device;

FIG. 4 is a rear elevational view of the device;

FIG. 5 is a top plan view of the device; and

FIG. 6 is a bottom plan view of the device.

I claim:

The ornamental design for a tape cutting device, as shown and described.
